UNITED STATES PATENT OFFICE.

CHARLES J. MILLER, OF MOSELLE, MISSISSIPPI.

RAILWAY SIGNAL DEVICE.

1,424,509.

Specification of Letters Patent. Patented Aug. 1, 1922.

Application filed January 3, 1921. Serial No. 434,671.

To all whom it may concern:

Be it known that I, CHARLES J. MILLER, a citizen of the United States, residing at Moselle, in the county of Jones and State 5 of Mississippi, have invented new and useful Improvements in Railway Signal Devices, of which the following is a specification.

My present invention pertains to railway 10 signalling devices, and it contemplates the provision of an automatic signalling arrangement whereby the engineer may readily determine the various positions of the semaphore arms that are used in connection 15 with railway operation and this irrespective of the weather conditions that prevail. The invention further contemplates a device of the character set forth whereby in foggy weather the engineer will be automatically signaled as to his whereabouts and 20 at the same time signaled as to whether he should proceed with or without caution, and hence when a train and railway are equipped with my novel invention, the movement of 25 a train may be carried on with safety and as expeditiously as in clear weather.

Other characteristic features of my invention will be readily understood from the 30 following description and claim when the same are read in connection with the drawings accompanying and forming part of this specification in which:

Figure 1 is a side elevation of a portion of track equipped with my novel device 35 and also showing a portion of engine and tender thereon.

Figure 2 is a perspective view of a railway track equipped with my novel trip for 40 actuating the engine signal and I have also in this view shown an approaching engine on said track.

Figure 3 is a side elevation of the trip and auxiliary tension rail in its operative position preparatory to engagement of the 45 valve lever of the engine.

Figure 4 is a view similar to Figure 3 but showing the auxiliary tension rail in its inoperative position.

Figure 5 is a top plan view of the auxiliary tension rail and trip as properly positioned with respect to the rails.

Figure 6 is a view taken in section of my novel trip valve.

Figure 7 is a rear elevation of the valve.

Figure 8 is a detail view of shoe that is

applied to the pilot of the engine to prevent injury to the trip on initial passage of the pilot over the trip.

Figure 8^a is a detail view of one of the rollers 53 and showing the arrangement of 60 the projections 56 thereof.

Figure 9 is a front elevation of the indicator that is properly arranged in the cab of the engine to apprise the engineer of his position on the road. 65

Figure 10 is a side elevation of the indicator with the casing removed in order to illustrate its working elements.

Figure 11 is a view showing a portion of the casing of the indicator broken away in 70 order to disclose the arrangement of the tapes and station or signal plates and the mechanism on which the plates and tapes move.

Similar numerals of reference designate 75 corresponding parts in all the views of the drawings.

Before entering into a detailed disclosure of the invention I deem it expedient to state that in order to maintain operation of railway trains at the maximum of safety, it is highly important that the engineer be fully aware as to whether the signals are clear or not and also his exact position on the road. During clear weather the indication 80 and positions of the signals regarding danger or clear conditions may be readily seen but in foggy weather the indications and positions of the signals is more or less guess work on the part of the engineer. My device not only positively indicates the warnings of the visual signals in all kinds of weather, but doubly assures the engine crew by means of my novel cab indicator. 85

The rail 1 and the ties 2 are of the ordinary well known construction, and on the inside of one rail, I secure a trip or trigger 4 by means of a plate member 3. This trigger 4 is of the construction illustrated and is fulcrumed to the track as indicated 90 by 5 and the trigger is further provided at one end with an eye 6, to which is secured a weight 7 that works in a casing 8. At its opposite end the trip is divided in a way to form a forked portion 9 to guide and 105 work in conjunction with my tension rail 10, at point 11 as shown in Figures 3, 4 and 5.

The rail 10 may be of any length or construction compatible with its purpose, and it will be noted that one rail securing lever 110

12 is of U-shaped form and is fulcrumed at 13 to the track and at 14 to the auxiliary rail 10. Manifestly this construction permits of upward and downward movement of rail 10 with respect to the stationary track rail 1.

The U-shaped link 12 is provided with an eye at 16 to receive a cable 15 that passes under a sheave 17 in the countersunk casting 18. At its opposite end the cable by preference is secured to the signal panel of the ordinary construction used in conjunction with railroad signalling.

Assisting the link 12 in its office of supporting the rail 10 is a U-shaped link 19 that in turn is fulcrumed at 20 to the track and also to the auxiliary rail 10 at 21. The link 19 is secured to a weight 22 at point 23. This weight 22 operates in a casing 24 adjacent the rail 10. To assist in the support of the rail 10 I provide equi-distant arms or levers 25 and when expedient the well known guard rail 26 may be employed between the rails 1 and 10 to care for the lateral movement of the train wheels.

As a further protection to the operating elements of my invention, I provide on the underside of the pilot 28 of the engine a shoe 27 which permits the smooth passage of the pilot (the lowest portion of a train with respect to the ground) over the trip 4 and rail 10.

This precaution of providing a shoe 27 is due to the fact that actuation of the springs 35 of the engine caused by various levels of the track 1 would bring about contact of the pilot and rail 10 and consequent injury to the device.

It will be seen that I provide on the well known arch bar of the tender, a bar 30 and this bar extends across the tender to the side opposite to that shown in Figure 1.

To this bar I secure a valve 31 that communicates with the main air signal pipe 32 by means of a short length flexible hose 33. The connection of short hose 33 and pipe 32 is the usual one of a T coupling 34. This construction permits the compressed air in pipe 32 to enter a chamber 35 (Fig. 6) and hence the valve port 36 is held in a normally closed position.

As clearly shown in Figure 7 the valve 31 comprises the two bolted sections secured to each other at 37 and provided with the hangers 38 that are bolted to the valve. In their lower ends the hangers 38 receive a bolt 39 that in turn acts as a fulcrum point for a depending arm 40. This arm is retained in its inoperative position by a spring clip 41 that retains the arm 40 in contact with a valve 42 at the point 43 thereof. The valve 42 is provided with the curved lower portion as illustrated and at its lower end the arm 40 is provided with a contact roller 44 (Figs. 6 and 7) that assures smooth

operation of the valve 42 upon contact with the rail 10.

When the valve 42 is moved upwardly by arm 40, the valve 36 will be unseated and this will compress a spring 45 that abuts against the piston of valve 36 and is arranged in the valve casing 31. Upon upward movement of the valve 36 compressed air in chamber 35 enters the chamber 46 and passes through the pipe 47 that is connected to a short flexible hose 48 (Fig. 1). This hose 48 is secured to an auxiliary conduit 39 that is arranged in and secured to the actuating casing 50 of a visual indicating device 51 (Fig. 9).

The indicator 51 comprises a casing 52 in which are arranged in suitable manner a series of rollers 53 and revolving on the rollers 53 is an endless belt or tape 54 (preferably of steel) having apertures 55 so constructed and arranged that they engage projections 56 of the rollers 53 whereby revolution of the rollers 53 will be attended by movement of the belt 54. Manifestly station or signal plates or both are arranged in spaced relation on the belt and at the proper point the casing 52 is provided with a sight opening as shown.

As shown in Figure 10, one of the rollers 53 has a small spur gear 58 fitted thereto to engage with the ratchet pawls 59 that are fulcrumed at 60 to the arm 61 which in turn is fulcrumed to the casing 52 at the point 62. The lever 61 has a lower portion 63 with apertures 64 and at 65 I arrange the brace member that receives the pin 60 and pin 67, the latter pin being referred to later in the description.

In order to prevent retrograde rotation of the tape, I retain the pawls 59 securely in the teeth of the spur wheel 58 by means of the tension spring 66. At 67 the arm 61 is connected to a piston rod 68 of the piston 69 which is retained in the actuating cylinder 50.

In the practical use of the invention the tension rail 10 is secured to the track along the left hand rail and connected to a signal by the cable 15 adjusted in a suitable manner so that when the signal arm indicates "clear" the cable pulls down the rail 10 level to the rail 1 by means of lever 12 and lifts the weight 22 and holds it to that position to prevent contact with lever 40 of valve 31 of the passing train. Manifestly the trip 4 will be operated at every passage of the train thereover, and said trip is returned to its normal (inoperative) position by means of the weight 7. The trip is only in a depressed position when a train passes thereover and at all other times is in the position shown in Figure 4. The weight assists in not only returning the trip to said position, but in maintaining it in said position. When the signal arm is at "stop" the cable

15 is loose or slack to allow the tension rail 10 to rise automatically to the required position due to the weight 22 falling. The trip 4 is held to its position by the weight 7 and 5 said trip always makes contact with lever 40 of valve 31 to register the passing of the signal on the indicator 51. Should the signal be at "stop" the rail 10 as well as trip 4 will likewise be elevated and the contact 10 of lever 40 of valve 31 with both trip 4 and rail 10, lifts the valve portion 36 permitting air to pass from the train pipe 32 through chamber 35 to chamber 34 and thence through hose 48 and auxiliary pipe 49 to 15 actuating cylinder 50 of the indicator 51 which actuates piston 69 and ratchet 59 to rotate spur 58 to change name plate of the indicator. When the signal is set at clear manifestly the trip 4 will contact with roller 20 44 of lever 40 of valve 31 that communicates with the well known signal pipe line. Said signal pipe line, for purposes of clearness, is that by which a conductor signals to the engineman. The trip flashes a short 25 audible signal to the engineman and indicates to him that "all is clear;" also it operates the station or position indicating means. However, when the signal is set at "stop" the rail 10 as well as trip 4 is raised above 30 the rail 1, which long rail 10 prolongs the audible signal. It should be borne in mind that in order to distinguish between certain conditions that prevail different lengths or duration of audible signals must be employed and hence the provision of the trip 35 4 for short signals and rail 10 for long ones.

The audible signal referred to in this specification is the well known whistle or air actuated signal by which the conductor 40 by pulling the train cord transmits signals to the engineer and therefore illustration of this signal is deemed unnecessary.

The air valve is operated by every contact with the mechanism and as contact with 45 trip 4 (Fig. 4) would be short the added provision of rail 10 with trip 4 in operation (Fig. 3) is to prolong the signal by keeping the valve open a longer period of time. The said opening of the valve permits air to 50 escape from the main signal pipe reducing the pressure, which operates a whistle in the cab of the engine, and which is a part of the present and well known system of train signalling, and my invention is an addition to said system of train signalling for 55 the purpose of connecting visual signals automatically. In the code of signals that are used by trainmen for different purposes, distinction is made by the length of 60 the blast or whistle, for instance _____

_____ 2 long and 2 short blasts;
_____ 1 long, 2 short

and 1 long; _____ 1 long; _____ 1 short, and hence the advantages of this device will be apparent. The addition of this device to 65 the signalling system will add materially to the safe operation of a train.

Immediately after passing over trip 4 and rail 10 the lever 40 returns to its normal position, the spring 45 pressing portion 70 36 to its seat and opens port 70. The spring 71 pressing back the piston 69 to normal position discharges air through port 70 and the device is ready for a subsequent operation. 75

I would distinctly have it understood that the device is intended for use on all forms and styles of railway equipment either steam or electric and the elements entering in to the invention may be of any size and material and embrace any departure in construction as fairly falls within the scope of the claim.

Manifestly the safety features of my construction are readily apparent to those 80 skilled in the art and because of the simple and positive operation of the device is a material factor in railroading irrespective of weather conditions.

Likewise the device may be readily and 85 inexpensively installed and maintained and comprises no delicate parts, such as are liable to get out of order after a short period of use.

Having described my invention, what I 90 claim and desire to secure by Letters Patent is:—

In an automatic signal device, the combination of a railway track, a trip fulcrumed adjacent the inside of one rail 100 thereof and normally resting above the rail, an auxiliary rail normally resting below the level of the track and movable upwardly and downwardly with respect to the track and being arranged in the same plane as 105 the trip and in advance thereof with respect to the direction of travel of a train, a valve secured to the train for controlling passage of air to the main signal line of a train, a 110 visual indicator arranged on the train, an arm secured to the valve and depending therefrom, and a signal arm arranged adjacent the track and connected with the auxiliary rail for elevating the same above the track to cause contact of the arm of the 115 valve with the auxiliary rail to actuate said valve.

In testimony whereof I have hereunto set my hand in presence of two subscribing witnesses.

CHARLES J. MILLER.

Witnesses:

L. M. CRANFORD,
J. W. COCKRELL.
